UNITED STATES PATENT OFFICE

AUGUST C. SPAHN, OF EVANSVILLE, INDIANA, ASSIGNOR TO BERNARDIN BOTTLE CAP COMPANY, OF EVANSVILLE, INDIANA, A CORPORATION OF INDIANA

SHEET METAL CAN

Application filed February 24, 1930. Serial No. 430,653.

The invention relates to cans and more particularly to that type in which the rim portion of the body can be torn off by a suitable key on a line below the can-top. In this type of can, it is now common practice to tear off the rim-portion of the body below the top, so as to leave a portion thereof attached to the top, and so it can be used as a cover after the can has been opened. This is objectionable, because the raw edges left on the metal of the can-body and the cover by the tearing are likely to cut the fingers of the user when the can is handled after the can has been opened.

One object of the invention is to overcome this objection by providing a removable cap for use on the can after the top has been removed, and which, when on the can, and while its top is sealed, will serve to provide a sealed chamber above the top for containing, against contamination, devices, such as a cup or spoon for serving or measuring the contents, and the key for opening the can.

Another object of the invention is to provide an improved cap for sealed cans which is adapted to be seated and sealed on the seam between the can-body and its top, and which, after the top has been removed from the can, will form an efficient closure to preserve the contents of the can and to cover the raw edge of the metal on the rim of the can where it has been torn in removing the top.

Other objects of the invention will appear from the detailed description.

The invention consists in the several novel features hereinafter set forth and more particularly defined by claims at the conclusion hereof.

In the drawing: Fig. 1 is a section of a can embodying the invention with the cap thereon, and Fig. 2 is a section of the can with a strip torn off so the can top can be removed. Fig. 3 is a section showing the cap applied to the can after the can-top has been severed from the body of the can. Fig. 4 is a perspective of the cap.

The invention is exemplified in a sheet metal can comprising a cylindrical body a , a bottom a' , secured to the body by a marginal seam a^2 , and a top a^3 secured to the body by a marginal seam a^4 . A ring b is secured

inside of the upper portion of the body and secured therein by a rolled-in bead b' . The metal forming the body a is adapted to be torn by a suitable key, a tab being usually provided on the body to enter a key by which an annular strip of metal may be torn out by winding the key around the periphery of the can, leaving a space a^5 (Fig. 2) to sever the top and a strip depending therefrom, from the body a , so the top can be removed to give access to the contents of the can. Ring b is beaded at its upper edge, as at b^2 , and forms a smoothly finished rim for the can-body after the top a^3 has been removed by tearing the body, as aforesaid.

A removable sheet metal cap comprises a top c and an integral depending skirt c' which is formed with an annular shoulder c which is adapted to seat on the seam a^4 . This shoulder is spaced from the top c of the cap to form a chamber d between the can-top a^3 and the top of the cap in which devices, such as a measuring cup or spoon e , and a key f for tearing off the rim-portion of the cap, are suitably secured, usually by tongues g soldered to the can top a^3 . The skirt of the cap extends below the shoulder c^2 and is provided with a series of insets c^3 which are spaced apart and in desired number to interlock frictionally with the seam a^4 and to hold the shoulder c^2 snugly seated on the top of the can and to seal the chamber d . The lower margin of the skirt is beaded, as at c^4 , to provide a finished lower edge of the cap. The portion of the skirt above the shoulder c^2 is of such diameter that it will fit snugly around the exposed upper portion of the outer periphery of the ring b after the top a^3 has been severed and removed from the can-body. The portion of the skirt of the cap below the shoulder is extended downwardly sufficiently to cover the torn edge on the can-body when the cap is placed thereon after the top a^3 has been removed and then the insets c^3 will frictionally grip the outer periphery of the can-body above the bead b' to hold securely, but removably, the cap thereon. Insets c^3 are spaced apart so the skirt portions between them will be sufficiently resilient to permit the insets to

spring over the seam a^4 in applying the cap to the can while it is sealed.

In packing goods which require sterilization, the cap is placed on the sealed and filled can, and sterilized therewith, so that the devices in the chamber d , as well as the contents of the can, will be sterilized. The insets c^3 securely hold the shoulder a^2 of the cap on the can and retain the devices sealed in chamber d and against contamination. When the contents of the can are to be used, the cap is first removed therefrom. The skirt of the cap being securely held on the can, the skirt may be loosened by tapping it until the insets c^3 can be sprung over the seam a^4 . The key f will then be accessible so it can be applied to the can-body, and wound around the outside thereof to tear a strip from the rim-portion of the can-body a below the top a^3 , to sever the top from the can-body, with a portion of the body left attached to the top a^3 by the seam a^4 . The top can then be thrown away. The cap is then applied to the can to serve as a removable closure. The cylindrical portion of the skirt above the shoulder c^2 will fit frictionally and snugly around the outer periphery of the exposed portion of the ring b to form a seal and the insets c^3 will frictionally grip the can-body below the torn edge thereon to assist in removably holding the cap on the can. The skirt, extending below the raw edge on the can-body, will cover said edge and prevent injury to the user. Insets c^5 are formed to cause the skirt of the cap above the shoulder c^2 to grip more firmly the ring b when the cover a^3 has been removed.

The invention exemplifies a sealed can with a top which can be removed by tearing the rim-portion of the can and a cap which provides a sealed chamber above the can for containing devices, and in which the skirt of the cap is formed with a shoulder for seating and sealing the top on the can, and with means for removably securing the cap on the can, and in which the cap is adapted to be fitted on and secured on the can-body after the latter has been torn to permit its top to be removed.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A sheet metal can comprising a cylindrical body, a circular top secured to and forming a seal for the top end of the body, the rim of the body adjacent the top being adapted to be torn off to remove the top, and a removable sheet metal cap having a circular top wall and a cylindrical skirt depending from the top wall and provided at the inter-

mediate part thereof with an annular shoulder seated on the marginal part of the top, the portion of the skirt above the shoulder forming with the top wall and the top a closed chamber over said top, the portion of the skirt beneath the shoulder embodying means engaging frictionally the rim of the body for removably securing the shoulder seated on the aforesaid marginal part of the top and being adapted, when the rim of the body has been torn off for the purpose of removing the top, to extend around the top end of the body to close the latter and to be held removably in place by engagement of the securing means with the portion of the body directly beneath its torn edge. 70

2. A sheet metal can comprising a cylindrical body, a circular top sealed and secured on the body by a seam at its margin, the rim of the body adjacent the top being adapted to be torn off to remove the top, and a removable sheet metal cap having a circular top wall and a cylindrical skirt depending from the top wall and provided at the intermediate part thereof with an annular shoulder seated on the seam, a portion of the skirt above the shoulder forming with the top wall and the top a closed chamber over said top, the portion of the skirt beneath the shoulder embodying arcuate insets engaging frictionally and interlocked with the seam for removably securing the shoulder seated on the seam, and being adapted, when the rim portion of the body has been torn off for the purpose of removing the top, to extend around the top end of the body to close the latter and to be held removably in place by engagement of the arcuate insets with the portion of the body directly beneath the torn edge. 85

sitioned so that the first-mentioned portion of the skirt fits slidably around the ring after removal of the rim portion and the top.

4. A sheet metal can comprising a cylindrical body with a rim portion at the top end thereof adapted to be torn off, a ring secured to the body so that it is positioned within the rim portion and adapted to form a rim for the top end of the body after the rim portion has been torn off, a circular top secured to and removable with the aforesaid rim portion of the body and forming a seal for the top end of the body, and a sheet metal cap comprising a top wall and a circular skirt depending from the top wall and provided at the intermediate part thereof with an annular shoulder seated on the marginal part of the top, the portion of the skirt above the shoulder forming with the top wall and the top a closed chamber over said top, being shaped to fit slidably around the ring after removal of the rim portion and the top and embodying indents for engaging frictionally said ring, the portion of the skirt beneath the shoulder embodying means engaging frictionally the rim portion of the body for removably securing the shoulder seated on the aforementioned marginal part of the top and being adapted to surround the top part of the body when the cap is positioned so that the first-mentioned portion of the skirt fits slidably around the ring after removal of the rim portion and the top.
5. A sheet metal can comprising a cylindrical body with a rim portion at the top end thereof adapted to be torn off, a ring secured to the body so that it is positioned within the rim portion and adapted to form a rim for the top end of the body after the rim portion has been torn off, a circular top secured to and removable with the aforesaid rim portion of the body and forming a seal for the top end of the body, and a sheet metal cap comprising a top wall and a circular skirt depending from the top wall and provided at the intermediate part thereof with an annular shoulder seated on the marginal part of the top, the portion of the skirt above the shoulder forming with the top wall and the top a closed chamber over said top and being shaped to fit slidably around the ring after removal of the rim portion and the top, the portion of the skirt beneath the shoulder embodying means engaging frictionally the rim portion of the body for removably securing the shoulder seated on the aforesaid marginal part of the top and being adapted, when the cap is positioned so that the first-mentioned portion of the skirt fits slidably around the ring after removal of the rim portion and the top, to surround the top end of the body and to be held removably in place by engagement of the securing means with

the portion of the body directly beneath the torn edge.

Signed at Chicago, Illinois, this 13th day of February, 1930.
